UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,234,238.

Specification of Letters Patent.

Patented July 24, 1917.

Application filed September 30, 1913. Serial No. 792,697.

To all whom it may concern:

Be it known that I, EDWARD J. VON PEIN, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash registers, accounting machines, and the like and more particularly to those machines in which independent cash receptacles are provided for the respective clerks for keeping their cash separate so that the responsibility of mistakes and shortages may be placed on the proper clerk and also to prevent misappropriation by one clerk of the cash in charge of another.

Cash registers having a plurality of cash drawers are usually so constructed that access can be had to the drawer by depressing a single key to predetermine which drawer shall be opened at a subsequent operation of the machine. Upon operation of the machine the selected drawer is released and records of one form or another are made by the machine in a record retaining device to show which drawer was opened, the nature and amount of the transaction, etc. Indicators as well as different toned bells are usually provided to indicate to the various clerks and the proprietor which drawer has been opened and enables each clerk to tell whether his drawer is wrongfully opened by another clerk.

The reason for having a number of cash drawers attached to the cash register is to give a separate receptacle for each attendant, thereby enabling the proprietor to place individual responsibility for errors and shortages and also to prevent one attendant from fraudulently withdrawing from the cash register money in charge of another attendant. The proprietor is able to learn whether the proper amount is in each attendant's receptacle by comparing the cash in the drawer with the records made in the machine of the various transactions registered. It is possible, however, for one clerk to open the cash drawer of another attendant when no one is present to detect his wrong doing by merely pressing the other clerk's key, the clerks' keys usually bearing characters, such as initials, to indicate which drawer is controlled by each key and which

belong to the various clerks. Such an opportunity for dishonesty is always present where there are several attendants, such as cashiers, employed each having a separate drawer but only one attendant being on duty at a time. The theft in such case could not be readily traced to the dishonest clerk or cashier and the clerk or cashier to whom the drawer was assigned would be made responsible for the defalcation which would be discovered by the proprietor on comparing the cash in the drawer with the records in the machine.

The main object of this invention is to eliminate as far as possible the opening by one clerk or cashier of the drawer in charge of another by improving the construction of the means controlling the opening of the drawers. In the illustrative form shown in the accompanying drawings the object of the invention is accomplished by providing means compelling the operation of a plurality of special keys in combinations, the keys being designed to control in certain combinations only the opening of the drawers. The drawer of each clerk is controlled by the operation of keys included in a certain corresponding combination, and as each clerk is to know only the combination for opening his individual drawer, one clerk cannot readily open the drawer of another. A plurality of detent plates are provided in the particular embodiment shown, one for each combination, and each of these detent plates can be moved only by the operation of keys of a corresponding combination. One of the keys in each combination is in the embodiment shown to control the extent of movement of a releasing means for the drawer while the last key operated in the combination, which may also be the key controlling the movement of the releasing means, disables a device normally locking the machine against operation to permit the subsequent operation of the latter. The detents are so constructed that final or complete movement of any one of them locks the keys not included in the combination moving the detent, against manipulation.

In the form shown the keys which are operable only in combination comprise a single bank and as a plurality of keys, two in the present case, are to be depressed at each operation of the machine the ordinary forms of detents for locking the operated

the stud 24 with the shoulder 25 on the arm 26 rocks the arm 26, shaft 16 and the arm 15 counter clockwise and in this way extension 14 on the arm 15 is drawn out of engagement with the disk 12 to permit operation of the machine.

The cash drawers 28 (Figs. 3 and 4) which in the embodiment are shown arranged in one vertical row are held shut by their catches 29 which have formed on their rear ends hooks 31 engaging drawer catch plates 32 fastened to the rear of the machine. It will readily be seen that in order to release any one of the desired drawers all that is necessary is to push the end of its drawer catch 29 down so that the hook 31 will disengage the plate 32. In the operation of the machine this is done by the catch trip lever 33 in the following manner. When the keys in the combination are depressed against the tension of their springs 34 and the register operated, a segment 35 (Fig. 1) is differentially positioned dependent upon which of the depressed keys is engaged by a trip pawl 36 of the latch 37 carried by the segment. The manner in which this is done is well known in the art and is fully explained in the Cleal and Reinhard patent above mentioned and reference may be had to this patent for a full description of the operation of these parts. The segment 35 has an extended rack portion 38 which is in engagement with a gear 39 fast to a shaft 41, to which is also fastened a bevel gear 401 and this bevel gear 401 meshes with a bevel gear 40 (Fig. 3). This latter gear is splined on a shaft 42 to permit a vertical movement of the shaft. It will readily be seen that any movement of the segment 35 will be transmitted to the shaft 42 causing the shaft to rotate extents determined by the movements of the segment. A coupling sleeve 43 rigidly connects the shaft 42 with the shaft 44 but this is only necessary for assembly purposes. Arranged around the shaft 44 which extends vertically in the rear of the drawers are drawer fingers 45 (Fig. 14), one for each drawer and these are so positioned that when the segment 35 is stopped by a certain one of the keys in a combination, one of the drawer fingers 45 will be under the drawer catch trip lever 33 for the drawer that corresponds to the combination of keys depressed.

The finger shaft is next raised so that the finger 45 for the drawer that is to be opened and which has been adjusted under its drawer catch lever will rock the appropriate lever 33 for the drawer to be selected about its pivot 35^a forcing the opposite end of the lever down against the end of the catch 29, and disengaging it from the plate 32. The drawer is then ejected from the cabinet 65 in the usual manner by a spring 46 which

is carried on the rear wall of the drawer and is compressed against the plate 32 when the drawer is given its full inward stroke.

The finger shaft 44 can be raised by any one of a number of different forms of lifting mechanism. In Figs. 1 and 3 of the drawings there is shown in dotted lines a conventional device comprising a pitman 50 and a cam 51, the cam being mounted on and near the right end of a drive shaft 52. The upper end of the pitman has a hook which engages over the drive shaft 52 and carries at its side a roller 55 resting on the cam 51 as shown. The enlarged lower end 47 of the pitman 50 has (Fig. 3) a vertical slot 48 through which the end of a lever 56 passes. The other end of this lever is pivoted to the frame of the machine while the lever intermediate its ends engages a collar 54 secured to the shaft 42. The cam 51 is rigidly fastened to the drive shaft 52 and as the shaft is turned during an operation of the machine the pitman 50 will lift the lever 56 and therefore through collar 54 the shaft 44 against the action of the spring 60 coiled about the shaft and compressed between the collar 54 and a flange 49 on the frame 49^a, thereby releasing the drawer that is to be opened.

The segment gear 35 meshes also with a gear 57 loosely mounted on the shaft 11. This gear 57 meshes with a pinion wheel 58 rigidly mounted on the side of an indicator 59 loosely mounted on a transverse shaft 61. The indicator bears initials or numbers corresponding to the drawers to indicate which drawer has been last opened, and it is clear that when the segment gear 35 is differentially moved the indicator will be given a like extent of movement.

All of the mechanism mentioned so far is old in the art and needs no more detailed description. The reason it has been covered to such extent is because some explanation is thought desirable to make the following description of the new mechanism more easily understood.

The improvement consists of means compelling the operation of the keys 1 to 9 in certain combinations to select the drawer to be opened and to unlock the machine, thus making it harder for one clerk or cashier to gain access to another's drawer. This is accomplished in the form shown by the employment of a plurality of detent plates 62 (Figs. 1, and 5 to 12 inclusive) any one of which is operated by keys in a corresponding combination only to move the plates 18 in order to unlock the machine so that the latter may be operated. The extent of movement of the differential segment gear 35 when the machine is operated is determined by one of the keys in the combination being engaged by the trip pawls 36 for the latch 37 tripping the latter to allow the driver 75

130

to go on, and arresting the movement of the segment 35. As these detent plates 62 compel the operation of the keys in combinations and lock certain of the keys against operation as will be explained, they will be hereinafter called "combination" detents. There is one of these detents for each combination and as there are nine keys, one for each drawer, nine combinations can be employed. Five of these "combination" detents are preferably arranged to the left of the plate 18 on the left side of the side frame 17 and four of them are mounted to the right of the plates 18 and on the right side of the frame supporting the keys. They are slidably mounted on the pins 20 in the same manner as are the plates 18, having the slots 63 and the elongated notches 64 through which the pins 20 pass similar to those described above as in the plates 18. A pin 65 on each plate 18 normally passes through the center of slots 66 in all the plates arranged along the side of the respective plates 18.

25 The keys as usual carry pins 67, but these pins project from both sides of the key shanks and pass over the forward edges of all of "combination" detents. When the first key in any combination, there being two 30 keys for each combination in the preferred form, is depressed, one of its pins 67 engages an inclined edge 68 of a projection 69 on the corresponding "combination" detent and raises the detent until the lower end of its 35 slot 66 is just in contact with the pin 65. Such movement of the detent brings an inclined edge 70 of a projection 71, which is shown narrower than the projection 69, into the path of the pin of the second key in the 40 combination of which the key depressed is the first. Depression of this latter key through the engagement of its pin 67 with the inclined edge 70 raises the combination detent one step further and as the lower end 45 of the slot 66 is then in engagement with the pin 65 on the plate 18, the plates 18 and the "combination" detent are moved together during this last step of movement of the latter. As hereinbefore described the final 50 increment of movement of the plates 18 through the engagement of the stud 24 with the shoulder 25 on the arm 26 rocks the shaft 16 counter-clockwise to lower the locking arm 15 out of engagement with the disk 12 55 so that the machine may be operated. When the second key is depressed the ends of the rectangular shaped projections 72 which are on the operated detent and are normally out of the path of the pins on the keys are moved 60 under the pins not belonging to the combination shifting the moved plate, so that the keys not included in this particular combination are locked against operation.

65 It is understood, of course, that the projections 69 and 71 on each "combination" de-

tent are similarly constructed, but differently arranged according to the combinations employed. Many combinations are possible but, of course, only as many combinations can be used as there are keys. Nine of 70 these "combination" detents are shown in Figs. 1 and 5 to 12 inclusive, but it is to be understood that any other detents constructed to be operated by keys in different combinations can be substituted, these being 75 shown merely for illustrative purposes. The combination for moving the detent plate shown in Fig. 1 is 37 as the 3 key and subsequently the 7 key are depressed to operate the same. Depression of the 3 key 80 through the engagement of the pin 67 with the inclined edge 68 of the projection 69 of the 37 "combination" detent, raises the detent so that the lower inclined edge 70 of the projection 71 may be brought into the path 85 of the pin on the 7 key which is the other key in the combination to be depressed. Operation of this latter key raises the detent still further to raise the plates 18 and cause the latter upon the last part of their movement to rock the arm 26 and thereby unlock the machine. It can readily be seen that 90 63 is the combination for moving the detent shown in Fig. 5, as the 6 and then the 3 key must be depressed to operate the detent, and that 26 is the combination for operating the detent shown in Fig. 6, as the 2 key and then the 6 key must be operated to actuate the detent. In a like manner it is obvious that the combinations of keys for moving the 95 "combination" detents shown in Figs. 7, 8, 9, 10, 11 and 12 are 49, 58, 95, 15, 78 and 81 respectively. If as shown in these figures the "combination" detents are so constructed that the nine projections 69 are adapted 100 to be engaged respectively by different keys only the selected detent would be raised upon operation of the first key in the combination, while the second key would raise this detent still further and give another detent, the inclined portion 68 of whose projection 69 was in the path of the pin on the second key, one extent of movement. With the projections 64 arranged differently it is clear that the number of plates actuated 105 would be dependent upon the arrangement of the projections 67 and the keys operated. 110

115 In those combinations which operate the four "combination" detents on the right side of the keys the lower key in each combination determines which drawer shall be opened. This is true as the lowest key is the first to be engaged by the trip pawl 36 to disconnect the latch 37 from the driving segment 75, the operation of the segment and the latch being fully described in the aforesaid Letters Patent granted to J. P. Cleal and F. A. Reinhard. As the lower key determines the extent of movement of the segment gear 35 in operations in which the ma- 120 125 130

chine is released by movement of the detent plates at the right of the keys, it determines which drawer shall be opened as the movement of the segment gear prepares the finger 45 for opening the drawer, as has been fully described. In order to permit the upper keys of combinations to operate the latch 37 so that their corresponding drawers may be opened, it is evident that means must be provided to prevent the lower keys in the combination from operating the latch. To this end the five "combination" detents on the left side of the side frame 17, which are the "combination" detents controlling the unlocking of the machine when one of the drawers corresponding to the five upper positions of the segment 35 is to be opened, are provided with V-shaped members 76 as shown in Figs. 1, 6, 7, 8 and 10. These members are pivoted on pins 77 to these "combination" detents and each is so positioned on its supporting detent that the end of the forward arm 78 of the V-shaped member is in the path of the lower key in the corresponding combination so that depression of this key rocks the member about its pivotal center and the inclined edge 80 of the rear arm 79 of the member is thereby held while the key is retained depressed in the path of the trip pawl 36, the upper end of the trip pawl being provided with a horizontally extending flange 85 which extends across the rear edges of the "combination" detents carrying these members 78. When the segment gear 35 is actuated, the trip pawl 36 engages only the arm 79 of the member rocked by the depressed key but the arm 79 deflects the trip pawl 36 from its normal course about the end of the key operating the V-shaped member and without being obstructed by the lower end of the depressed key as the trip pawl is allowed to be pressed rearward about its pivot 84 against the action of its spring 81. As the trip pawl 36 passes out of engagement with the arm 79 and around the lowermost depressed key its spring 81 pushes it forward to normal position so that it will engage the end of the upper depressed key and thereby trip the latch 37. Leaf springs 82 project from the members 78 between their arms and engage pins 83 on their combination detents and serve to restore the members to initial position after the depressed combination keys are returned outward to normal position upon being released and to normally hold the members out of the path of the arms 79 as shown.

With the fingers 45 helically arranged on the finger shaft 44 as is usual in the art the drawer to be opened is in the same relative position in the tier of drawers that the key limiting the extent of movement of the segment gear 35 and thereby controlling the opening of the drawer, is in the bank. With the fingers 45 so arranged that one key of

every combination is readily ascertained by all of the clerks, a clerk could press the known key of another clerk's combination, which bears the same relation to the other keys as does the drawer opened by such clerk to the other drawers, and then by depressing the other keys until the other key of the combination is found, open the drawer assigned to the other clerk. To eliminate as far as practical the possibility of one clerk ascertaining another combination and opening the drawer of such other clerk the fingers 45 in the preferred form shown have been staggered on the finger shaft so that the drawer to be opened is not in the same relative position in the row of drawers that its controlling key in the combination is in the bank.

For example in the preferred form, the finger 45¹ (Fig. 14) is the fourth finger from the top of the shaft and is for opening the fourth drawer from the top and its angular position is 252° from the position in which it will engage, when lifted, the drawer catch trip lever 33 for the fourth drawer. As one step of movement of the segment gear 35 rotates the finger shaft 36° it is evident that the segment gear 35 moves seven steps before the finger 45¹ which is 252° from operating position is in operative relationship with its respective drawer catch trip lever 33, and therefore as the "3" key stops movement of the segment gear 35 at the end of its seventh step of movement, the combination 37 (Fig. 1) controls the opening of the fourth drawer in the tier. The finger 45² is the seventh finger from the top of the shaft 44 and is for unlocking the seventh drawer and is 144° from the position in which it will engage, when raised, the drawer catch trip lever 33 for the seventh drawer and therefore the combination 63 (Fig. 5) controls the opening of the seventh drawer. In a like manner the finger 45³ is the third from the top of shaft 44 and eight steps of movement, the finger 45⁴ is the fifth from the top of shaft 44 and is 6 steps of movement, and the finger 45⁵ is the sixth from the top of shaft 44 and is 5 steps of movement from their positions in which they when raised will engage their respective trip levers 33 and the combinations 26, 49 and 58 (Figs. 6, 7 and 8 respectively) control the opening of third, fifth and sixth drawers respectively. The combinations 95, 15, 75, and 81 (Figs. 9, 10, and 12 respectively) which effect the positioning of fingers 45⁶, 45⁷, 45⁸ and 45⁹ respectively eighth, second, first and ninth from the top of shaft 44, control in a similar manner the opening of the eighth, second, first and ninth drawers respectively. Of course it is obvious that the arrangement of these fingers 45 can be varied as desired so that the combinations shown can

6
open drawers other than those assigned to the combinations in the illustrations above. With the fingers arranged as just described it is clear that the initial or numbers on the indicating disk are to be arranged accordingly so that the character displayed by the indicator will correspond to the number of the drawer opened or the initial of the clerk to whom the drawer is assigned.

The means for locking the keys in operated positions is shown in Fig. 13 and this means will now be described. Nine locking dogs 90 are pivotally mounted by pins 89 on a plate 91. The plate 91 is slidably mounted at the left of the last "combination" detent to the left of the keys, on the pins 20 which pass into the slots 92 in the plate. The locking dogs 90 are bell crank in form and their forward arms form hooks and have inclined faces 93 normally in the path of the end of the pins 67 projecting from the left side of the keys. The other arms of the dogs are provided with flanges 94 which are normally in engagement with the rear edge of the plate 91 and so held in that position by also being in engagement with the periphery of a segment plate 95. At its rear end the segment plate 95 is bifurcated and straddles the transverse shaft 96 and near its periphery carries a pin 97 passing into a slot 98 formed in a projection 99 of the plate 91. A spring 100 which is under tension between a pin 101 on a projection 99 and a pin 102 on the plate 95 tends to pull the plate 95 forward to keep the locking dogs in normal position. When a key is depressed its pin 67 engages the inclined face 93 of its locking dog and rocks the latter counter-clockwise, as viewed in Fig. 13, and as the pin passes off the inclined face the plate 95, through the spring 100, restores the detent to normal position so that the upper wall of the recess 104 below the inclined face 93 will engage over the pin 67 on the key to retain the key in depressed position. In this manner it will be seen that as each key is depressed its corresponding locking dog will lock it in depressed position without operating the other dogs so that two keys can be operated in the bank during the same operation of the machine.

Near the end of the operation of the machine the shaft 96 is rocked upward past the normal position (shown in Fig. 13) as described in the above mentioned Cleal and Reinhard patent and an arm 105 fast to the shaft is thereby brought into engagement with an anti-friction roller 106 mounted on the segment plate 95 to rock the plates 95 and 91 as a unit, they being connected as described by the pin 97 on the plate 95. As the locking dogs 90 are held by the plate 95 from moving relatively to the plate 91 upon move-

ment of the plates 91 and 95 it can readily be seen that the recesses 104 of the dogs in locking relationship with the keys will be carried out of engagement with the pins on the depressed keys so as to permit the 70 springs 34 coiled about the key shanks to force the keys outward to their normal position. After the keys are released the plates 95 and 91 are returned by a spring 111 attached at one end to the frame and at the 75 other to the plate 95, to lower and normal positions.

The plate 91 and also, through the pin 97, the plate 95 may be moved upward to release any key depressed in error before the 80 actuation of the operating mechanism by rocking a shaft 108 carrying an arm 109 clockwise as the lower end of the plate is in engagement with this arm. The shaft 108 is connected with a special manipulative arm 85 or device but as this key releasing mechanism is old in the art it need not be described in detail herein.

So far as applicant is aware there has been prior to this no drawer releasing mechanism controlled by manipulative means operable only in combinations and it is intended that the claims included herein should cover all the various forms of embodiment of which the invention is susceptible. It is apparent that any particular number of drawers is not essential to the successful operation of the improvement and also that any number of combination keys may be employed as desired. 100

While the form of mechanism herein shown and described is admirably adapted to fulfil the objects primarily stated, it is to be understood that it is not intended to confine the invention to the one form of 105 embodiment shown and described herein, as it is susceptible of embodiment in various forms, all coming within the scope of the claims which follow.

What is claimed is:— 110

1. In a machine of the class described, the combination with a plurality of drawers and latches therefor; of depressible keys the operation in a certain order of two of the keys being necessary for predetermining which 115 drawer shall be unlatched; and operating means for unlatching the selected drawer.

2. In a machine of the class described, the combination with a plurality of drawers; of means for holding them in closed position in the machine; a series of depressible keys, the operation in a certain order of a plurality of the keys always being necessary for predetermining which drawer shall be opened; and common means for releasing any selected drawer upon operation of the machine. 125

3. In a machine of the class described, the combination with a plurality of normally inaccessible drawers; of a plurality of ma- 130

nipulative devices operable in combinations for predetermining which drawer shall be rendered accessible; and operating means for rendering the selected drawers accessible.

5. In a machine of the class described, the combination with a plurality of normally inaccessible drawers; of a corresponding number of manipulative devices operable in combination for predetermining which 70 drawer shall be rendered accessible; and operating means for rendering the selected drawer accessible.

10. In a machine of the class described, the combination with an element to be moved differentially; of a main operating mechanism for driving said member; and a single bank of keys, a plurality of which are operable at one operation of the machine for predetermining the extent of differential 75 movement to be imparted to said element.

15. In a machine of the class described, the combination with an indicator; of an actuator therefor; a bank of keys, a plurality of which are operable for predetermining in a 80 single operation of the machine the extent of movement of the actuator.

20. In a machine of the class described, the combination with an indicator; of an actuator therefor; operating means for driving the same; and a single bank of keys, operable in combinations for predetermining the extent of movement to be given the actuator by the operating means.

25. In a machine of the class described, the combination with a plurality of drawers; of a single bank of keys, operable in combinations for predetermining which drawer shall be opened; means for locking the keys in operated position; and operating means 95 for opening the selected drawer and for causing said locking means to release said keys.

30. In a machine of the class described, the combination with a differentially movable element; of a bank of keys, operable in combinations for predetermining the extent of movement of the differentially movable element; a plurality of members one adjacent each key for locking the keys in operated 100 position; and a movable plate carrying said members and adapted to be moved during the operation of the machine to cause said members to release the keys.

35. In a machine of the class described, the combination with a bank of keys; of a plurality of bell crank levers one adjacent each key for locking the same in operated position; a sliding plate having said levers pivoted thereto; and operating means for moving said plate to cause said levers to release the operated keys.

40. In a machine of the class described, the combination with a plurality of keys; of a corresponding number of pivoted dogs each of which is adapted to be rocked by a

corresponding key to lock the latter in operated position; and means for bodily moving all of the locking dogs to cause the same to release the operated keys.

45. In a machine of the class described, the combination with a plurality of keys; of a corresponding number of pivoted dogs, each of which is adapted to be rocked about its pivot by a corresponding key to lock the latter in operated position; operating means 75 for bodily moving all of the locking dogs to cause the same to release the operated keys; and manipulative means for bodily moving all of the locking dogs for the same purpose and before the machine is operated. 80

50. In a machine of the class described, the combination with a plurality of keys; of a corresponding number of pivoted dogs bell crank in form and adapted to be rocked by corresponding keys to lock the latter in operated position; a sliding member carrying said locking dogs; means for moving said sliding member; and a plate engaging one end of the locking dog to normally hold the same in locking position and for causing 90 the same to move bodily with the sliding member whereby the operated keys are released.

55. In a machine of the class described, the combination with a plurality of keys; of a corresponding number of pivoted dogs, bell crank in form, and adapted to be rocked by corresponding keys to lock the latter in operated position; a sliding member carrying said locking dogs; a spring drawn plate 100 engaging one end of the locking dogs and so connected to the sliding member that rocking of the locking dogs operates the plate to hold the locking dogs in locking position; and means for moving the plate and the sliding member, whereby because of the engagement of plate with the locking dogs, the latter are moved with the sliding member to release the operated keys.

60. In a machine of the class described, the combination with a plurality of keys; of a corresponding number of pivoted locking dogs, bell crank in form and adapted to be rocked by corresponding keys to lock the latter in operated position; a sliding member carrying said locking dogs; operating means for positively moving said member; a plate engaging one end of the locking dogs to normally hold the same in locking position and for causing the same to move bodily 110 with the sliding member whereby the operated keys are released; and spring means for returning the sliding member and locking dogs to normal position after the keys are released.

65. In a machine of the class described, the combination with a plurality of drawers; of a differentially movable element for determining which drawer shall be opened; a driving member therefor; a latch for con- 115 120 125 130

necting said differentially movable element and said driving member; keys operable in combinations and when operated being in the path of movement of said latch; and 5 means operated by certain keys only in certain combinations for moving the latch out of normal course so that another key in the combination may be engaged by said latch to disconnect the latter from the driving member and thereby determine the extent of movement of the differentially movable element.

17. In a machine of the class described, the combination with a plurality of drawers; of a differentially movable member for determining which drawer shall be opened; a driving member therefor; a latch for connecting said differentially movable member and said driving member and carrying an 10 element movably mounted thereon; a series of keys operable only in combinations and when operated being in the path of movement of the element movably mounted on the latch; and devices, operated by certain keys 15 only when the keys are in certain combinations, and constructed to deflect the path of movement of the movably mounted element, about the key operating the device so that another key in the combination may be engaged by said movably mounted element to 20 operate the latch and thereby determine the extent of movement of the differentially movable determining member.

18. In a machine of the class described, the combination with a plurality of drawers; of a differentially movable member for determining which drawer shall be opened; a driving member therefor; a latch for connecting said differentially movable member 25 and said driving member and carrying an element movably mounted thereon; a series of keys which when operated are in the normal path of movement of the element movably mounted on the latch; and devices, operated by certain keys only when the 30 keys are in certain combinations, and constructed to deflect the path of movement of the movably mounted element about the key operating the device so that another key in 35 the combination may be engaged by said last mentioned member to operate the latch and thereby determine the extent of movement of the differentially movable determining member; and means for restoring the 40 operated device to normal position.

19. In a machine of the class described, the combination with a main operating mechanism; of a device for normally locking the same against operation; a plurality 45 of keys operable in combinations; a plurality of movable elements, each of which is given a movement by each key in a corresponding combination to disable said locking means when the last key in the combination is operated.

20. In a machine of the class described, the combination with a main operating mechanism; of a device for normally locking the same against operation; a plurality of keys operable in combinations; a plurality 50 of movable elements each of which is given a movement by each key in a corresponding combination to disable said locking means when the last key in the combination is operated, and also to lock the unoperated 55 keys against operation.

21. In a machine of the class described, the combination with a plurality of drawers; of operating means for opening the same; a locking device normally locking said means from operation; and a plurality of manipulative devices operable in combinations, the operation of one manipulative device predetermining the drawer to be opened, while operation of a second manipulative device in coöperation with the first 60 disables said locking means.

22. In a machine of the class described, the combination with a plurality of drawers; of operating means for opening the same; a locking device normally locking said means against operation; and a plurality of manipulative devices operable in combinations for predetermining which drawer shall be opened and for disabling the locking 65 means.

23. In a machine of the class described, the combination with a main operating mechanism; of a series of keys; a locking device for the operating mechanism; a sliding plate, movement of which disables said locking device; a member slidably mounted on said plate and slid on the same upon operation of a key so that the subsequent operation of a certain other key moves the member and the plate together to disable the locking device.

24. In a machine of the class described, the combination with a main operating mechanism; of a locking device normally locking the same against operation; and a plurality of keys operable in combinations for disabling said locking means.

25. In a machine of the class described, the combination with a main operating mechanism; of a locking device normally locking the same against operation; a member for disabling said locking device; plates slidable on said member; and a plurality of manipulative devices operable in combinations for first moving one of said plates relatively to said member and subsequently moving both the member and the plate to disable the locking means.

26. In a machine of the class described, the combination with a main operating mechanism; of a locking device normally locking the same against operation; a member for disabling said locking device; plates slidably mounted on said member; and a

plurality of manipulative devices operable in combinations for first moving one of said plates relatively to said member and subsequently moving both the member and the plate to disable the locking means and lock the unoperated keys against operation.

27. In a machine of the class described, the combination with an element to be differentially moved; of a driving member therefor; a latch for connecting the element and the driving member together; a locking device normally locking the driving member from movement; and a single bank of keys operable in combinations, the first key operated regardless of its position in the bank, being adapted to coöperate with the latch to determine the different points at which the latch is disconnected from the driving member and the second key in coöperation with the first key being employed to disable the locking means for the driving member.

28. In a machine of the class described, the combination with a group of drawers; of a differentially movable member for controlling the opening of said drawers; and manipulative means operable only in combination and constructed to control the differential adjustment of the differentially movable member controlling the opening of the drawers the adjusted position of the differentially movable member being in a different position relative to its other adjusted positions, than the selected drawer is with reference to the group of drawers.

29. In a machine of the class described, the combination with a bank of character bearing keys operable in combinations; of an indicator bearing as many characters as there are keys, and adapted to be controlled by the operation of the keys in combinations so that each character displayed by the indicator may not correspond with the character on any of the keys of the corresponding combination.

30. In a machine of the class described, the combination with a plurality of drawers; of an indicator for indicating which drawer is opened; and manipulative means operable only in combinations for controlling the opening of the selected drawers and the extent of movement of the indicator.

31. In a machine of the class described, the combination with a group of drawers; of a series of keys operable only in combinations for predetermining which drawer shall be opened, the relative position of the selected drawer in the group being different than the relative position in the series of any of the keys of the corresponding combination; and an indicator for indicating which drawer is opened.

32. In a machine of the class described, the combination with a plurality of drawers; of a plurality of manipulative devices operable in combinations each combination of

devices being employed to control the opening of a corresponding drawer; and means for preventing the operation of the manipulative devices included in the combinations if other manipulative devices than the manipulative devices included in their respective combinations are operated.

33. In a machine of the class described, the combination with a plurality of drawers; of a plurality of manipulative devices operable in combinations, each combination of manipulative devices being employed to control the opening of a corresponding drawer; and means for preventing the operation of the manipulative devices included in the combination if other than the manipulative devices included in the respective combinations are operated, and also for preventing the operation of manipulative devices not in the respective combinations after the manipulative devices in the respective combinations are operated.

34. In a machine of the class described, the combination with a plurality of keys operable in combinations; of means controlled by said keys; a plurality of movable elements each of which is given a movement by each key in a corresponding combination, and constructed to lock a key in the combination against operation if a key other than one included in the combination is operated.

35. In a machine of the class described, the combination with a plurality of keys operable in combinations; of means controlled by said keys; a plurality of movable elements each of which is given a movement by each key in a corresponding combination and constructed to lock a key in the combination against operation if a key other than those included in the combination is operated; and means for manually releasing the operated keys.

36. In a machine of the class described, the combination with a plurality of keys operable in combinations; of means controlled by said keys; and a plurality of movable elements each of which is given a movement by each key in a corresponding combination and constructed to lock a key in the combination against operation if a key other than those included in the combination is operated, and also constructed to lock all the keys other than those in a combination against operation after the keys in the combinations have been operated.

37. In a machine of the class described, the combination with a single bank of keys, operable in combinations, each combination including two keys; of means controlled by said keys; and means preventing the operation of the last key operable in a combination if a key not included in the combination is operated after the first key of the particular combination is operated.

38. In a machine of the class described, the combination with a main operating mechanism; of a plurality of keys operable in combinations; means controlled by said keys; means normally locking the operating mechanism against operation; and a plurality of plates each having inclined projections adapted to be engaged by the keys in the corresponding combination to move 10 said plate and thereby disable the locking means.
39. In a machine of the class described, the combination with a plurality of keys operable in combinations; of means controlled by said keys; means normally locking the machine against operation; and a plurality of plates each having inclined projections adapted to be engaged by the keys in the corresponding combination to move 15 said plate and thereby disable the locking means, said plates also having other projections for locking the keys other than those in the combination operating the plates against operation.
40. In a machine of the class described, the combination with a plurality of keys operable in combinations; of means controlled by said keys; a plurality of plates having inclined projections one inclined projection being normally in the path of the first key to be operated in a corresponding combination so that when such key is depressed another inclined projection, which is on the plate and normally out of the path 20 of the last key operable in the combination, is moved into the path of the last key whereby operation of this last key moves the plate still farther; and means controlled by said plate.
41. In a machine of the class described, the combination with a plurality of keys operable in combinations; of means controlled by said keys; a plurality of plates having inclined projections one inclined projection being normally in the path of the first key to be operated in a corresponding combination so that when such key is depressed another inclined projection, which is on the plate and normally out of the path 25 of the last key operable in the combination, is moved into the path of the last operable key whereby operation of this last key moves the plate still further, said plates also having other projections which, when a plate 30 is operated by the keys of a corresponding combination, are moved into the path of the other keys to lock the latter against operation; and means controlled by said plate.
42. In a machine of the class described, the combination with a plurality of keys operable in combinations; of means controlled by said keys; a plurality of plates, each plate having inclined projections adapted to be engaged by the keys of a corresponding combination, and also having 35
- projections which when a key other than those included in a combination is depressed, engages said key to prevent operation of all of the keys in the combination.
43. In a machine of the class described, the combination with a plurality of keys operable in combinations; of means controlled by said keys; a plurality of plates one for each combination and each having projections adapted to be engaged by the 40 keys in the corresponding combination to move the respective plate, said projections being so constructed that when it is attempted to operate the keys of a combination in a reverse order the last key in this reverse order is locked against operation.
44. In a machine of the class described, the combination with a plurality of drawers; of a differentially movable member for determining which drawer shall be opened; a plurality of keys operable only in combinations for limiting the extent of movement of said member; and means operated by keys in certain combinations to render one of said keys in each of these certain combinations ineffective for limiting the extent of movement of said differentially movable member.
45. In a machine of the class described, the combination with a bank of keys operable in combinations; of devices controlled by keys which are operable in certain combinations and nearer one end of the bank than the other keys in these certain combinations; and means for rendering the keys 50 nearer the end above mentioned than are the other keys in other combinations ineffective when the keys nearer the end mentioned are operated in other combinations so that the other keys in these other combinations may control said devices.
46. In a machine of the class described, the combination with a plurality of keys operable only in combinations; of a device controlled by certain keys in certain combinations; and means for rendering the certain keys mentioned ineffective for such purpose when these keys are operated in other combinations than those mentioned.
47. In a machine of the class described, the combination with a plurality of keys operable in combinations; of a device controlled by certain of said keys in certain combinations; a plurality of plates having inclined projections adapted to be engaged 55 by the keys operable in the remaining combination to move said plates; and means actuated by the certain keys first mentioned when those keys are operated in the remaining combinations to render those keys when 60 operated in such remaining combinations ineffective to control said device.
48. In a machine of the class described, the combination with a plurality of keys operable in combinations; of a device con- 65

trolled by certain of said keys in certain combinations; a plurality of plates having inclined projections adapted to be engaged by the keys operable in the remaining combination

5 combination to move said plates; and members pivoted on said plate and in the path of the certain keys mentioned when they are the last keys operated in the remaining combinations so that these keys are rendered ineffective to control said device.

49. In a machine of the class described, the combination with a plurality of cash drawers, of latches therefor, means common to said latches for selectively releasing the latches, and a plurality of keys movable independently of the releasing means and operable in various fixed combinations to control said means.

50. In a machine of the class described, the combination with a plurality of normally inaccessible cash drawers, of mechanism common to said drawers for selectively rendering the drawers accessible, and a plurality of keys movable independently of 25 and operable in various fixed combinations to control said mechanism.

51. In a machine of the class described, the combination with an operating mechanism, of a device normally locking same 30 against operation, a bank of keys, and means requiring operation of said keys in predetermined pairs and the keys of the pair in an invariable sequence to disable said locking device.

52. In a machine of the class described, the combination with an operating mechanism, of a device normally locking same against operation, a bank of keys arranged 40 to permit operation of a plurality of said keys, and means coöperating with and controlled by various combinations of said keys for rendering the locking device ineffective.

53. In a machine of the class described, the combination with an invariably moved 45 element, of a differentially movable element, a latch for connecting the invariably moved element and the differentially movable element, a bank of keys depressible in prearranged combinations for disabling the 50 latch at different points in the movement of the invariably moved element, and means rendered effective when a key is depressed in one combination for preventing said key from disabling the latch, said means being

ineffective to prevent the same key from disabling the latch when said key is pressed in a different combination.

54. In a machine of the class described, the combination with a plurality of normally inaccessible receptacles, of mechanism 60 common to said receptacles for selectively rendering the receptacles accessible, and manipulative devices operable in combinations known only to the respective clerks and the proprietor to control the operation of said 65 mechanism.

55. In a machine of the class described, the combination with a plurality of cash drawers, one for each clerk, of a latch for each drawer, mechanism common to said 70 latches for selectively tripping the latches, and keyboard mechanism comprising a plurality of clerks' keys operable in combinations known only to the respective clerks and the proprietor to control the operation 75 of the latch tripping mechanism.

56. In a machine of the class described, the combination with a plurality of normally inaccessible clerks' cash drawers, of a series of keys consisting of one key for each 80 drawer, and means requiring operation of the keys in combinations known only to the respective clerks and the proprietor and the keys of each combination in an invariable sequence for rendering the different drawers 85 accessible.

57. In a machine of the class described, the combination with a driving mechanism, of devices normally preventing operation of said mechanism, and keyboard mechanism 90 comprising a plurality of clerks' keys operable in combinations known only to the respective clerks and the proprietor to disable said devices.

58. In a machine of the class described, 95 the combination with a driving mechanism, of a normally effective lock for said mechanism, a bank of clerks' keys, and means requiring operation of said keys in combinations known only to the respective clerks 100 and the proprietor to render the aforesaid lock ineffective.

In testimony whereof I affix my signature in the presence of two witnesses.

EDWARD J. VON PEIN.
